UNITED STATES PATENT OFFICE.

GEORGE HORNELL THACHER, JR., OF NORTH PROVIDENCE, RHODE ISLAND.

STOKER.

Application filed January 23, 1920. Serial No. 353,423.

To all whom it may concern:

Be it known that I, GEORGE H. THACHER, Jr., a citizen of the United States, residing at North Providence, in the county of Providence, State of Rhode Island, have invented certain new and useful Improvements in Stokers; and I do hereby declare the following to be a full, clear, and exact description of the invention, such as will enable others skilled in the art to which it appertains to make and use the same.

This invention relates to an improvement in hand stokers of the general type shown and described in my Patent No. 1,302,453, granted April 29, 1919, wherein the stoker bars and cleaning grates are mounted to rock on inclined bearing-bars extending from the front to the rear of the furnace, and wherein the stoker bars are connected together usually in two series, to rock independently, whereby to advance the fuel toward the cleaning grate and to clean the stoker bars.

An object of the present invention is to provide an improved arrangement for holding the inclined bearing-bars in place in the furnace, in such manner that while they cannot move bodily in either direction, they may freely expand and contract under temperature changes without affecting the operation of the stoker, and to provide an improved form of coking plate.

A further object is to provide an arrangement for facilitating the assembling or disassembling of the grate sections.

The particular nature of the several features of the invention, as well as other advantages thereof will appear most clearly from a description of certain preferred embodiments as shown in the accompanying drawings, in which:

Fig. 1 is a section through a furnace showing the entire stoker in side elevation but with parts in section;

Fig. 1^a is a perspective view of the upper end of one of the bearing bars.

Fig. 2 is a plan view of the bearing bars and coking plate;

Fig. 3 shows the cross-bearing bar and coking plate as viewed from the interior of the furnace, the bearing bars being shown in transverse section;

Fig. 4 shows the coking plate as viewed from the opposite direction;

Fig. 5 is a transverse sectional view of

the coking plate along the line 5—5 of Fig. 4, and Fig. 6 is an end view of the same on the line 6—6 of Fig. 4.

Fig. 7 shows the cross-bearing bar.

Referring to the drawings, 1 indicates the front wall of the furnace, 2 the bridge wall, and 3 and 4 the side walls. The front wall is provided with a suitable number of doorways 5 closed by fire-doors. A supporting member or box 6 is embedded in each of the side walls near the inner face of the front wall, and these members are adapted to receive the ends of a cross-bearing bar 7, which extends parallel to the inner face of the front wall, but is spaced a short distance therefrom, as shown most clearly in Fig. 1. The cross-bearing bar is provided with a number of notches 8, into which are fitted the upper ends of the inclined bearing bars 9, upon which the stoker bars and cleaning grates are mounted. The entire stoker will in general be made up of several units, each comprising a number of stoker bars with a cleaning grate at the bottom of the incline. The bearing bars 9 may be of any suitable construction, but are here shown as consisting of an upper main portion 10, provided with a number of curved recesses 11 for receiving the trunnions of the stoker bars and cleaning grate. The bearing bars may be strengthened by bracing members 12 extending from one end to the other. The upper end of each bearing bar is provided with a horizontal surface as at 13 adapted to rest upon the bottom of one of the notches 8 in the cross-bearing bar 7, and in order to hold the bearing bar in place there is provided a lug 14 integral with the inclined bearing bar which engages the outer face of the cross-bearing bar, as shown most clearly in Fig. 1. By virtue of the construction thus described, the upper end of each bearing bar is immovably attached to the cross-bearing bar 7, but in order to allow for expansion of the bearing bars, their lower ends are mounted in boxes 15 embedded in the bridge wall 2 of the furnace, in such a manner that the ends of the bearing bars may move freely in the boxes as the bars expand or contract, due to changes in temperature.

Mounted upon the cross-bearing bar at the top of the stoker are coking plates 16, of which any desired number may be used. The construction of these coking plates appears most clearly in Figs 3, 4, 5 and 6.

Each plate comprises a frame 17 provided with depending portions 18 which are adapted to fit between the cross-bearing bar 7 and the inner face of the front wall of the furnace as shown most clearly in Fig. 1. The bottom of the frame comprises horizontal portions 19, above the outer ends of which is an inclined plate 20, the lower edge of which lies closely adjacent the upper edge of the topmost stoking bar and the upper edge of which engages the inner face of the front wall of the furnace, preferably at the bottom of the doorways 5 through which fuel is introduced. The plate 20 is provided with a number of apertures 21 through which air may enter to burn off the volatile constituents of the green fuel at the top of the fire-bed. As here shown, the apertures are in the form of two series 20 of long narrow slots, but it will be understood that they may be of any other form. The bottom member of the frame 17 is provided with notches 22 adapted to fit over the upper ends of the bearing bars when the 25 coking plate is in place, as shown most clearly in Fig. 3. To aid in holding the coking plate in place upon the cross-bearing bar, one or more lugs 23 are provided. These lugs project from the bottoms of the 30 horizontal portions 19 and are adapted to engage the inner face of the cross-bearing bar, as shown most clearly in Fig. 1.

In the construction illustrated in Fig. 1, each stoker bar comprises a pair of side members 24 equipped with trunnions which fit in the recesses 11 (Fig. 2) in the inclined bearing bars. The side members 24 are connected by a curved shield 26 preferably formed integral with the side members. 40 Each shield may be provided with a number of apertures as illustrated and described more in detail in my Patent No. 1,302,453. Attached to each curved shield 26 is a lug 29 by means of which the stoker bars are operatively connected to actuating mechanism.

As shown most clearly in Fig. 1, the lug 29 of each of the several stoker bars forming the upper portion of the apparatus is connected to a rod 31 which is provided with a depending portion 32, to which is connected a rod 33 extending through an aperture in the front wall of the furnace and connected to a lever 34 mounted on a bracket 35. The upper end of the lever is formed to enter a socket in a suitable hand bar for manipulating the lever and connecting rods to tilt the stoker bars. The lugs 29 of the series of stoker bars forming the lower portion 60 of the apparatus are connected to a second bar 31 by means of which these stoker bars may be operated independently of the upper series of stoker bars by means of a second rod 33 and lever 34. As shown 65 in the illustrated embodiment of the inven-

tion, each half of the stoker is made up of four stoker bars, but it will be understood that any other number may be used and that any number of adjacent bars may be connected together into a series, the bars 70 of which may be operated independently of those of other series.

The grate surface of each grate bar is detachably secured to a transverse supporting bar 42, the ends of which are bolted to 75 the side members 24 as shown and described more in detail in my Patent No. 1,302,453.

Grate surfaces suitable for use in the present invention are described and claimed in my copending divisional application, Serial 80 No. 433,595, filed December 28, 1920, and a somewhat different construction is disclosed and claimed in my copending divisional application, Serial No. 433,596.

In assembling the stoker bars the lugs 29 85 may be attached to the shields 26 at the desired point to permit the connecting rods 31 and the actuating rods 33 to occupy the correct position with respect to the levers 34 at the front of the furnace. The cleaning 90 grate at the bottom of the incline over which the coal passes comprises side members 48 connected by a curved shield 50 carrying a lug which is pivotally attached to an operating rod 60. The perforate grate surface 53 95 is detachable and overlaps the upper edge of the curved shield 50 as described and claimed in my divisional application, Serial No. 433,669, filed December 28, 1920, patented Nov. 21, 1922, No. 1,436,215.

In the operation of the stoker of the present invention, combustion of the fuel takes place primarily upon the stoker bars, but air may also pass through the notches in the cleaning grate to burn any unconsumed fuel 105 which may reach this grate. As shown most clearly in Fig. 1, the upper edge of each stoker bar lies closely adjacent to the serrated lower edge of the adjoining bar. The curved shields 26 prevent fuel from dropping between the bars when they are rocked, but apertures in the shields permit sufficient air to enter the fuel bed when the stoker bars are tilted to prevent any appreciable decrease in combustion.

The fuel bed may be advanced toward the cleaning grate from time to time by first tilting the cleaning grate to dump the accumulated ashes therefrom and then tilting the lower series of stoker bars by manipulation of the lever 34 associated therewith to cover the cleaning grate with hot coals and ashes. The lower series of stoker bars is then restored to normal position and the upper series manipulated by its lever 34 to 125 tilt these bars and advance the upper portion of the fuel bed over the lower series of bars. Green fuel may be supplied at the top of the fuel bed from time to time as required. The coking plate 16 will permit 130

a sufficient amount of air to be supplied to the green fuel to burn off the volatile constituents.

Any one of the units of the coking plates 5 16 may be removed for repair or replacement by simply lifting it off of the cross-bearing bar 7. If at any time it becomes necessary to remove any of the bearing bars 9 the stoker bars and cleaning grates 10 mounted thereon will be removed, and the bearing bars may be quickly taken out by lifting their upper ends off of the cross-bearing bar 7 and freeing their lower ends 15 from the supporting members in the bridge wall of the furnace.

While certain preferred embodiments of the various features of the invention have been shown and described, it will be understood that various changes in the details of 20 construction of these several features may be made without departing from the principle of the invention as defined in the appended claims.

I claim:

25 1. In a hand stoker having inclined bearing bars, and stoker bars mounted to rock thereon, a fixed supporting bar at the upper ends of the bearing bars and fixed bearing boxes for the lower ends of the bars, the bearing bars having hooked engagement 30 with the supporting bar, and sliding engagement with the boxes, thereby to permit expansion and contraction without distortion of the bearing bars, the supporting bar 35 being notched to receive the bearing bars thereby to prevent lateral movement of the upper ends of the bearing bars.

2. In a hand stoker having inclined bearing bars and a plurality of stoker bars 40 mounted to rock on the bearing bars, the combination of a fixed supporting bar for

receiving the upper ends of the bearing bars, said bearing bars having lugs engaging the face of the supporting bar remote from the bearing bars for holding the bearing bars 45 in place, and means for slidably supporting the lower ends of the bearing bars for permitting said bars to expand and contract, the supporting bar being recessed to receive the bearing bars to prevent lateral movement 50 thereof with respect to the supporting bar.

3. In a hand stoker having inclined bearing bars and a plurality of stoker bars mounted to rock on the bearing bars, the combination of a supporting bar upon which 55 the upper ends of the bearing bars rest, and an inclined coking plate mounted on the supporting bar and provided with depending members adapted to engage one side of the bar and depending lugs adapted to engage the other side of the bar whereby the plate may be held in place on the bar with its lower edge adjacent the upper edge of the topmost stoker bar, said plate being provided with apertures through which air may 60 pass to the fuel at the top of the stoker.

4. In a hand stoker having inclined bearing bars, and stoker bars mounted to rock thereon, a fixed supporting bar at the upper ends of the bearing bars and fixed bearing 70 boxes for the lower ends of the bars, the bearing bars having hooked engagement with the supporting bar, and sliding engagement with the boxes, thereby to permit expansion and contraction without distortion 75 of the bearing bars, and a perforate plate supported in inclined position by the supporting bar extending from the grate bars above the supporting bar.

In testimony whereof I affix my signature. 80

GEORGE HORNELL THACHER, Jr.
